United States Patent Office.

LOUIS LEHMAN, OF BUFFALO, ASSIGNOR TO DANIEL W. FISH, OF BROOKLYN, NEW YORK.

Letters Patent No. 104,966, dated July 5, 1870.

IMPROVEMENT IN SPIKE-EXTRACTOR.

The Schedule referred to in these Letters Patent and making part of the same

I, LOUIS LEHMAN, of the city of Buffalo, county of Erie and State of New York, have invented a new and improved Spike-Puller, of which the following is a specification.

My improved instrument consists of a pry-bar, provided with the usual claw at the end, with which is combined an arrangement of levers by which the spike, after it has been loosened by prying in the ordinary manner, is drawn vertically upward without bending the same.

In the accompanying drawing—

Figure I is a view of my improved implement represented in the first act of loosening a spike by prying.

Figure II is a view of the same in the position it is just as the spike is drawn.

Figure III is a view showing the manner of using the instrument when a second prying movement becomes necessary.

Figure IV is a front sectional view.

Like letters of reference designate like parts in each of the figures.

A is the main bar, with the lower end curved, and provided with claws in the usual manner.

B is a bent lever, pivoted to the upper side of the bar, near its lower end.

C is a fulcrum-post, forked so as to pass astride of the bar A, and pivoted at its upper end to the short arm of the lever B, with its lower end widened, so as to form a suitable base or support as it rests on the ground.

D is an arm, pivoted at one end to the long arm of the lever B, and united at the other with a similar arm, D', which is hinged to the bar A near its upper end, forming a toggle-joint.

E is a lever, hinged at one end to the lever A, near its center, and

F is a link connecting the toggle-joint and this lever, all as clearly represented in the drawing.

In drawing spikes with my improved instrument, the claw is engaged with the head of the spike, and the latter pried loose in the usual manner, as shown

in Fig. I, by pressing down on the upper end of the bar A.

The bar is now held in this depressed position with one hand, while with the other the lever E is forced forward into the position shown in Fig. II, when the post C, resting on the ground, forms at its upper end a fulcrum for the bent lever, which elevates the lower end of the bar A, and withdraws the spike by a lifting action, as clearly represented.

In some cases the spike may be so firmly wedged in the tie or other timber that it is difficult to elevate it by the movement just described, after a single pry with the bar A. In such case the end of the bar is raised, so as to bring the notches c, which are formed in the edges of the forks of the post, in engagement with pins or spurs a, which project from the sides of the bar A when the locked post forms a second and higher fulcrum, that enables another prying movement to be made with the bar, which sufficiently loosens the spike to enable its further withdrawal to be readily accomplished by the auxiliary lever, as above described.

The arrangement of the lever E and toggle-joint enables the lever B to be more conveniently operated and the power to be applied with greater efficiency, than by taking hold of the latter lever directly.

What I claim as my invention is—

1. The combination, with the bar A, of the lever B and fulcrum-post C, substantially as and for the purpose hereinbefore set forth.

2. The combination and arrangement of the jointed bars D D', lever E, and connecting-arm F, with the bent lever B, post C, and bar A, substantially as hereinbefore set forth.

3. The arrangement, with the bar A and post C, and bent lever B, of the pins a and notches c, as and for the purpose hereinbefore set forth.

LOUIS LEHMAN.
